UNITED STATES PATENT OFFICE.

CHARLES B. BUSHNELL, OF MANSFIELD, OHIO.

MOP-WRINGER.

1,179,694.

Specification of Letters Patent. Patented Apr. 18, 1916.

Application filed December 3, 1915. Serial No. 64,886.

To all whom it may concern:

Be it known that I, CHARLES B. BUSHNELL, a citizen of the United States, residing at Mansfield, in the county of Richland and State of Ohio, have invented certain new and useful Improvements in Mop-Wringers, of which the following is a specification.

My invention relates to wringers and more particularly to a mop wringer.

The primary object of my invention resides in the provision of a novel wringer means for association with a receptacle, the wringer means being actuatable after a mop has been placed therebetween, to efficiently wring the mop, novel guarding means being associated with the wringer means for preventing the mop from clogging between the ends of the wringer means, including the rollers and the guide bars and thus prevents the mop from sticking and tearing and also more or less interfering with the efficient wringing of the mop.

Another object of my invention resides in the provision of improved brackets for slidably mounting the wringing rollers, the brackets serving to guide the rollers during the operation and also being formed so that the guarding means are readily provided.

A still further object of my invention resides in the provision of a device of the character described that is simple in construction, efficient in operation, and one that can be manufactured and placed upon the market at a minimum cost.

Other objects as well as the nature, characteristic features and scope of my invention will be more readily understood from the following description taken in connection with the accompanying drawings and pointed out in the claim forming a part of this specification.

In the drawings:—Figure 1 is a perspective view of one of the brackets; Fig. 2 is a top plan view of my invention associated with a receptacle; and Fig. 3 is a vertical sectional view of a receptacle showing my invention associated therewith and illustrating to advantage the novel manner of positioning the wringer rollers and the formation of the guarding means.

Referring more particularly to the drawings in which similar reference numerals designate like and corresponding parts throughout the different views, I provide a

receptacle, to the inner sides of which extend my improved brackets 2. Each of these brackets consists of an elongated body 3 having an elongated longitudinal guiding slot 4 therein for a purpose to be hereinafter described. The ends of the brackets are bent angularly to provide securing ears 5. The ears are in turn provided with openings 6 for receiving suitable fastening devices 7, the latter serving to rigidly yet removably connect the brackets at opposite points of the inner periphery of the receptacle adjacent the upper edge thereof. Each of the brackets is offset adjacent one terminal to provide arcuate shoulders 7', while ears 8 having openings 9 therein extend from the top and bottom edges thereof. A brace 10 is formed integral with the lower edge of each of the brackets and also integral with the lower ear or extension 8. A lateral flange 11 extends from the lower edge of each brace and serves as a guard in a manner to be hereinafter described. The flanges or guards 11 are arranged in a plane at an acute angle to the plane of the lower edge 80 of the bodies 3 as illustrated to advantage in Fig. 3 of the drawings. Wringing rollers 12 are interposed between the brackets and have their reduced ends rotatably mounted in the openings 9 in the ears 8, said rollers 85 being positioned directly above each other. Another roller 13 has the respective ends thereof arranged in the slots 4. A yoke 14 has outwardly bent arms 15 arranged in close relation with the outer sides of the 90 brackets and connected to the projecting reduced ends of the roller 13. The crown portion 16 of the yoke is bent outwardly and is pivotally connected through the medium of a suitable pin 17 to one end of a lever 18, 95 the opposite end of which lever is fulcrumed through the medium of a pin 19 to an ear 20 on a base plate 21, the latter being rigidly connected to the lower outer surface of the receptacle through the medium of a suitable 100 fastening device 22. A foot lever 23 has the inner end thereof pivotally connected to an ear 24 on the base plate through the medium of a suitable fastening device preferably a pin 25. Links 26 have the respective ends 105 thereof pivoted upon opposite sides and intermediate the ends of the levers 18 and 23. To normally hold the roller 13 at the outer end of the slots 4 in a position so that a mop can be readily placed between the 110

rollers 12 and 13, I have provided a substantially U-shaped spring 27, the vertex of which bears against the links 26 while the arms are arranged in straddled relation with 5 the links. Coils 28 are formed in the arms of the spring 27 adjacent the inner ends thereof while the extreme outer ends are rigidly connected to the base plate as illustrated by the numeral 29.

10 The operation of my invention is as follows: A mop is placed between the rollers 12 and 13 and the foot lever is pushed downwardly which causes the links to pull the upper end of the lever 18 outwardly and 15 simultaneously cause the yoke to be pulled downwardly. During this movement, the roller 13, which is arranged in a plane intermediate the planes of the rollers 12, is pulled outwardly against the mop and clamps the 20 latter against the rollers 12 and 12, the shoulder 7' serving to limit the movement of the roller 13 and relieve the strain from the reduced ends. While the roller 13 is clamping the mop, the guards 11 serve to guide 25 the mop toward the intermediate portions of the rollers and prevent the mop from clogging between the ends of the rollers and the guide bars, which usually causes the mop to stick and to tear, the guards thereby serving 30 to aid in the efficient wringing of the mop. Of course, after the mop has been clamped, by pulling upwardly between the rollers, it will be wrung whereupon the foot lever 23 can be released to allow the spring to return 35 the roller 13 to its clamped position so that another mop can be subsequently wrung.

Although I have shown and described the preferred embodiment of my invention, I desire it to be understood that I am not to 40 be limited to the exact details shown, however, I desire that great stress be laid upon the arrangement of the novel brackets for mounting and guiding the wringing rollers

as well as the guards formed when the 45 brackets are cast.

From the above description taken in connection with the accompanying drawings, it can be easily seen that I have provided a device that is simple in construction, containing but a few simple parts that can be 50 cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of the parts may be made within the scope of the appended claim and without 60 sacrificing any of the advantages of my invention.

Having thus fully described my invention, what I claim as new and desire to secure by Letters Patent, is:—

The combination with a receptacle, of slotted brackets secured to and extending across the receptacle, shoulders provided on said brackets, laterally extending flanges formed on the brackets and serving as mop 70 guides, relatively fixed rollers journaled in the brackets and arranged one above the other, another roller slideable in the slotted brackets, a yoke associated with the free ends of the movable roller, means for operating the yoke to consequently operate the movable roller, and said shoulders limiting the movement of the movable roller during the actuation of the yoke.

In testimony whereof I affix my signature 80 in presence of two witnesses.

CHARLES B. BUSHNELL.
